UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 29, 1928. Serial No. 112,500.

My invention relates to railway traffic controlling apparatus, and particularly to apparatus of the type comprising train carried governing means controlled by energy received from the trackway.

I will describe one form of railway traffic controlling apparatus embodying my invention, and will then point out the novel features thereof in claims.

10 The accompanying drawing is a diagrammatic view illustrating one form of railway traffic controlling apparatus embodying my invention.

Referring to the drawing, the reference characters 1 and 1^a designate the track rails of a stretch of railway track over which traffic normally moves in the direction indicated by the arrow. These rails are divided, by means of insulated joints 2, to form a plurality of track sections, only one of which, A—B, is illustrated in the drawing. As here shown each track section is provided with a trackway signal which is controlled in accordance with traffic conditions by means forming no part of my present invention and omitted from the drawing for the sake of simplicity. These signals may be of any suitable form and are here shown as semaphore signals each designated by the reference character S with an exponent corresponding to the location and each capable of displaying a proceed, a caution or a stop indication. Associated with signal S^b are two circuit controllers C and D. Circuit controller C comprises a movable lever 7, and circuit controller D comprises a movable lever 10. Levers 7 and 10 are controlled by signal S^b to swing into engagement with selected ones of fixed contacts associated therewith in accordance with the position of the signal, as will be clear from the drawing.

Train controlling current is at times supplied to the rails of section A—B by a track transformer T. The primary 4 of this transformer is constantly supplied with alternating current from secondary 5 of a line transformer L, the primary 6 of which is supplied with alternating current from an alternator M.

50 Associated with transformer T is a slow releasing relay R. This relay is provided with a circuit over which current flows from secondary 5 of transformer L, through wires 15 and 16, contact 7—8 of circuit controller

C, wire 17, back contact 14 of relay R, wire 18, winding of relay R, and wires 19 and 20 back to secondary 5 of transformer L. This circuit is closed only when signal S^b indicates caution or proceed, under which condition current will be supplied to relay R 60 over its own back contact. The relay therefore becomes energized. This energization of the relay opens back contact 14 thereon so that the circuit just traced for the relay becomes interrupted. After a time interval due to the slow releasing characteristics of the relay, the back contact 14 again closes and current is again supplied to the relay. It follows as long as signal S^b indicates caution or proceed, relay R is operated intermittently. Due to the slow releasing characteristics of the relay, its front contact 21—21^a is closed for a longer interval of time than its back contact 21—21^b during each complete cycle of operation of the relay. 75 When signal S^b indicates stop, circuit controller C is open and relay R is continuously de-energized.

The supply of train controlling current to the rails of section A—B by secondary 3 of transformer T is controlled by circuit controller D and by relay R. The left-hand terminal of secondary 3 of transformer T is constantly connected, through wire 22, with rail 1^a of section A—B. The right-hand terminal of this secondary is at times connected with rail 1 of the section through wire 25, contact 10—11 of circuit controller D, wire 26, front contact 21—21^a of relay R, and wires 27 and 28. This circuit is closed only when signal S^b indicates proceed and front contact 21—21^a of relay R is closed. When signal S^b indicates caution the right-hand terminal of secondary 3 of transformer T is connected through wire 25, contact 10—12 of circuit controller D, wire 29, back contact 21—21^b of relay R, and wires 27 and 28 to rail 1 of section A—B. This circuit is closed only when signal S^b indicates caution and relay R is open. When signal S^b indicates caution or proceed, however, relay R is operated intermittently as has been explained hereinbefore. It follows, therefore, that when either of the two circuits just traced is closed, current is supplied to the rails of section A—B in the form of code impulse combinations made up of impulses of energy separated by time intervals. The

relative lengths of the time intervals that alternating current is supplied to the track rails for the code impulse combination corresponding to the proceed and caution indications of signal S^B may be regulated by properly designing the relay R. For example, I will assume that a complete cycle of operation of relay R occupies one second, and that front contact 21-21^a is closed for two-thirds of a second and back contact 21-21^b is closed for one-third of a second during each such complete cycle. When signal S^B indicates proceed, therefore, code impulse combinations are supplied to the trackway according to the proceed code which comprises impulses of energy each lasting for two-thirds of a second and separated by time intervals of one-third of a second. When signal S^B indicates caution however, code impulse combinations are supplied to the trackway in accordance with the caution code which comprises impulses of energy of one-third of a second duration separated by time intervals of two-thirds of a second.

When signal S^B displays a stop indication, the right-hand terminal of secondary 3 of transformer T is then connected directly with rail 1 of section A-B over wire 25, contact 10-13 of circuit controller D and wires 30 and 28. When this circuit is closed alternating current is supplied to the rails of section A-B without interruption.

It is understood that each track section is provided with apparatus similar to that just described for section A-B.

The reference character V indicates a train which is provided with receiving apparatus designated in general by the reference character W. This receiving apparatus comprises two magnetizable cores 23 and 23^a carried by the train in inductive relation with the two track rails 1 and 1^a respectively, and located in advance of the forward axle of the train. Core 23 is provided with a winding 24, and core 23^a is provided with a similar winding 24^a, the two windings 24 and 24^a being connected in series in such manner that the voltages induced therein by alternating currents flowing in opposite directions in the two track rails at an instant are additive. The windings 24 and 24^a are connected, through an amplifier 31 with a relay K. Relay K is therefore energized during each impulse of alternating current supplied to the rails by transformer T. Associated with this relay is a transformer Q comprising a core 33 provided with a primary 34 and a secondary 35. A slow releasing relay designated by the reference character J is connected with secondary 35 of transformer Q through an asymmetrical unit 36. Primary 34 of transformer Q is provided with one circuit which may be traced from a suitable source of direct current such as a battery F,

through wire 37, front contact 32 of relay K, wire 38, primary 34 of transformer Q, wire 39, back contact 40-40^b of relay J, and wires 41 and 42 back to battery F. This circuit is closed only when relay J is deenergized and when relay K is energized. The current then builds up to a steady value in primary 34 and creates a magnetic flux in core 33. The asymmetrical unit 36 is so arranged that when the circuit just traced is closed the growth of the magnetic field created by the current in primary 34 creates a voltage in secondary 35 which tends to send a current through relay J in a direction contrary to the direction in which the asymmetrical unit 36 conducts more readily. It follows that when relay K next becomes deenergized the decay of this field induces in secondary 35 a voltage which tends to send through relay J a current which flows in the opposite direction from that created in this relay by the increasing field. It follows that the current caused to flow in secondary 35 of transformer Q by the decaying field flows in the direction in which the asymmetrical unit 36 conducts more readily. Due to the slow releasing characteristics of relay J, this relay maintains its front contacts closed during the interval which elapses between successive surges of energy supplied to the relay J during the caution or proceed codes. When relay J is energized a second circuit is completed for primary 34 of transformer Q which may be traced from battery F, through wire 37, front contact 32 of relay K, wire 38, primary 34 of transformer Q, wire 39, front contact 40-40^a of relay J, wire 43, winding of relay H, and wires 44, 45, 46, 47, and 42, back to battery F. When this circuit is closed, the electromotive force of battery F is connected across the terminals of primary 34 and relay H in series. Due to the reactive impedance of primary 34 the current resulting from this electromotive force increases slowly to its maximum value. It follows that a time interval elapses after the closing of the circuit including relay H before the current through the relay increases to the value necessary to pick up the relay.

In explaining the operation of the apparatus as a whole, I will first assume that signal S^B indicates proceed so that the rails of section A-B are being supplied with code impulse combinations in accordance with the proceed code. Assuming that relay J is deenergized, the first time contact 32 of relay K closes a surge of direct current flows through primary 34 of transformer Q over back contact 40-40^b of relay J. This surge of energy does not cause a current to flow in relay J. At the end of the impulse relay K becomes de-energized and the energy stored in the magnetic field of transformer Q is

supplied to relay J during the decay of this field, causing relay J to become energized. Front contact 40-40^a is therefore closed so that when relay K next becomes energized the closing of front contact 32 supplies a surge of direct current through primary 34 of transformer Q and also through relay H. As has been explained hereinbefore the current through the relay H increases slowly. 10 The parts are so proportioned, however, that when the relay K is closed for two-thirds of a second, as is the case when the proceed code is being supplied to the trackway, a sufficient time elapses for relay H to become 15 energized. Due to the slow acting characteristics of relays J and H, these relays keep their front contacts closed as long as relay K is intermittently operated in accordance with the proceed code. With both these relays 20 energized current flows from battery F, through wire 48, front contact 50-50^a of relay J, wire 49, front contact 51-51^a of relay H, wire 52, lamp 55 and wires 45, 46, 47, and 42, back to battery F. Lamp 55 is therefore 25 lighted to indicate proceed.

I will now assume that signal S^b indicates caution so that section A-B is supplied with code impulse combinations in accordance with the caution code. The first 30 impulse of this code closes contact 32 of relay K and builds up the current in primary 34 of transformer Q, and the subsequent opening of front contact 32 during the time interval between successive impulses 35 in the trackway allows the decaying field of transformer Q to create a voltage in secondary 35 which energizes relay J. Front contact 40-40^a of relay J is therefore closed so that the next succeeding impulse in the 40 trackway, by closing contact 32 of relay K, connects relay H in series with primary 34 across battery F. The proportioning of the parts is such that when front contact 32 is closed for only one-third of a second as is 45 the case when the trackway is being supplied with the caution code, the reactive impedance of primary 34 retards the growth of current in relay H to such an extent that the current in the relay does not increase to 50 a value sufficient to energize the relay before the relay circuit is again opened. When the train is being supplied with code impulse combinations in accordance with the caution code, relay J is continuously energized, but the comparatively short impulses 55 which are supplied to relay H under these conditions are not sufficient to energize this relay so that its back contact 51-51^b remains closed. Under these conditions, current 60 flows from battery F, through wire 48, front contact 50-50^a of relay J, wire 49, back contact 51-51^b of relay H, wire 53, lamp 56 and wires 46, 47 and 42, back to battery F. Lamp 56 is therefore lighted to 65 indicate caution.

When signal S^b indicates stop, uninterrupted alternating current is supplied to the rails of section A-B so that relay K is continuously energized. Current is continuously supplied from battery F, through primary 34 of transformer Q and back contact 40-40^b of relay J. Since the magnetic field in transformer Q is constant in value no current is supplied to relay J and this relay is continuously de-energized. Relay H is 70 also de-energized so that current flows from battery F, through wire 48, back contact 50-50^b of relay J, wire 54, lamp 57 and wires 47 and 42, back to battery F. Lamp 57 is therefore lighted to indicate stop. 75

It should also be pointed out that should the supply of alternating current to the rails of the section for any reason be interrupted, relay K would be continuously de-energized. Relay J would then be continuously de-energized and lamp 57 would be lighted to 80 indicate stop.

It will therefore be seen that relay J is a checking relay which is energized when interrupted current is supplied to the trackway according to either code, but that relay H is a selecting relay which is responsive to the length of each impulse supplied to the trackway and is energized only if these impulses are of the length corresponding to 90 the proceed code. 95

Although I have herein shown and described only one form of railway traffic controlling apparatus embodying my invention, it is understood that various changes and modifications may be made therein within the scope of the appended claims without departing from the spirit and scope of my invention. 100

Having thus described my invention, what I claim is:

1. In combination, a source of direct current, a relay, and means for at times periodically connecting said relay with said source for different intervals of time, such means including a reactive impedance connected in series with said relay to retard the growth of current in the relay so that the relay is responsive to the lengths of the intervals during which it is connected with the source. 110 115

2. In combination, a train carried relay, means for periodically energizing said relay for different intervals of time, a source of direct current, a second relay, a circuit for said second relay including a contact of said train carried relay and said source, an inductive reactance included in said circuit for retarding the growth of current in said second relay, and governing means selectively controlled by said second relay in accordance with the lengths of the intervals during which such relay is connected with the source. 120 125

3. In combination, a transformer having a primary and a secondary, means for supply- 130

- ing the primary with a series of direct current impulses, a relay, and means for supplying current to said relay from the secondary of said transformer during the decay 5 of the magnetic field created by each such impulse in the primary of the transformer but not during the growth of such magnetic field.
4. In combination, a train carried transformer having a primary and a secondary, means located partly in the trackway for at times supplying the primary of said transformer with impulses of direct current, a relay, means for supplying current to said relay from the secondary of said transformer during the decay of the magnetic field created by each such impulse in the primary of the transformer but not during the growth of such magnetic field, and governing means controlled by said relay.
5. In combination, a transformer having a primary and a secondary, means for supplying the primary with a series of direct current impulses, a relay connected with 25 the secondary of said transformer and an asymmetrical unit connected in series with said relay to permit current to flow through the relay during the decay of the magnetic field created by each impulse in the primary 30 of said transformer but to prevent the flow of current in said relay during the growth of such field.
6. Railway traffic controlling apparatus comprising a stretch of railway track supplied at times with periodic impulses of current, a first relay responsive to such impulses, a transformer having a primary and a secondary, means controlled by said first relay for periodically supplying the primary 35 of said transformer with direct current impulses, an asymmetrical unit, a second relay connected with the secondary of said transformer through said asymmetrical unit, a third relay, means controlled by said second 40 relay for at times connecting said third relay in series with said primary, and governing means controlled by said third relay.
7. Railway traffic controlling apparatus comprising a stretch of railway track supplied at times with periodic impulses of current, a first relay responsive to such impulses, a transformer having a primary and a secondary, means controlled by said first relay for periodically supplying the primary 50 of said transformer with direct current impulses, an asymmetrical unit, a second relay connected with the secondary of said transformer through said asymmetrical unit, a third relay, means controlled by said second 55 relay for at times connecting said third relay in series with said primary, and governing means controlled by said third relay.
8. Railway traffic controlling apparatus comprising a stretch of railway track supplied at times with periodic impulses of current, a first relay responsive to such impulses, a transformer having a primary and a secondary, means controlled by said first relay for periodically supplying the primary 60 of said transformer with direct current impulses, a second relay, means controlled by said second relay for periodically supplying the primary of said transformer with direct current impulses, an asymmetrical unit, a third relay, means controlled by said third relay for at times connecting said third relay in series with said primary, and governing means controlled by said third relay.
- plied at times with periodic impulses of current, a first relay responsive to such impulses, a transformer having a primary and a secondary, means controlled by said first relay for periodically supplying the primary 70 of said transformer with direct current impulses, a second relay, means for supplying current to said second relay from the secondary of said transformer only during the decay of the magnetic field created by each 75 impulse in said primary, a third relay, means controlled by said second relay for at times connecting said third relay in series with the primary of said transformer and governing means controlled by said second and 80 third relays.
9. Railway traffic controlling apparatus comprising a first train carried relay, means located partly in the trackway for periodically energizing said relay, a source of direct current, a transformer having a primary and a secondary, a second relay connected with the secondary of said transformer, a third relay; a circuit for the primary of said transformer including said 85 source, a front contact of said first relay, and a back contact of said second relay; a second circuit for such primary including said source, a front contact of said first relay, a front contact of said second relay, and the winding of said third relay; and governing means controlled by said second and third 90 relays.
10. Railway traffic controlling apparatus comprising a train carried relay, means located partly in the trackway for at times periodically supplying the relay with comparatively short impulses of current, and for at other times periodically supplying the relay with comparatively long impulses of 100 current, a second relay arranged to be energized when said first relay is receiving impulses of either length, a third relay controlled by said first and second relays and energized only when said first relay is receiving said long impulses, and governing means controlled by said second and third 105 relays.
11. Railway traffic controlling apparatus comprising a train carried relay, means located partly in the trackway for at times periodically supplying the relay with comparatively short impulses, and for at other times periodically supplying the relay with comparatively long impulses, a slow releasing relay, a source of current, means for connecting said slow releasing relay with said source during each such impulse, a reactive impedance in series with said slow releasing relay for retarding the growth of current in the relay so that the slow releasing relay becomes energized only when said train carried relay is receiving said long impulses, and governing means controlled by said slow releasing relay.
12. In combination, a first relay, means 115

for at times supplying said first relay with impulses of one length and for at other times supplying the relay with impulses of a different length, a transformer having a primary and a secondary, means for supplying direct current to the primary when said first relay is energized, a second relay receiving energy from the secondary of said transformer during the decay of the magnetic field created by each impulse in the primary of the transformer, a third relay connected in series with the primary of said transformer when said second relay is energized such third relay being energized when the first relay is receiving impulses of one length but not when the first relay is receiving impulses of the other length, and governing means controlled by said second relay.

13. Railway traffic controlling apparatus comprising means for supplying the trackway with interrupted alternating current in such manner that current flows in the trackway for different proportions of a given interval of time, a first train carried relay

selectively responsive to the proportion of such interval of time that current is supplied to the trackway, a second train carried relay responsive to such interrupted current, and governing means controlled jointly by said two relays.

30

14. Railway traffic controlling apparatus comprising means for at times supplying the trackway with interrupted alternating current in the form of impulses of energy separated by time intervals, a first train carried relay energized during such impulses but not during such time intervals, a second train carried relay controlled by the first relay and responsive to alternate energization and de-energization thereof, a third train carried relay controlled by the first relay and selectively responsive to the relative average lengths of such impulses and time intervals, and governing means controlled jointly by said second and third relays.

35

In testimony whereof I affix my signature.

ROBERT M. GILSON.
